UNITED STATES PATENT OFFICE.

JOHN WILLIAM WADSWORTH, OF DRAYTON, ENGLAND, ASSIGNOR TO EDWARD J. RIDGWAY, OF LIVINGSTON, NEW YORK.

DESIGN FOR A PLATE OR SIMILAR ARTICLE.

43,793.

Specification for Design.

Patented Apr. 1, 1913.

Application filed December 24, 1912. Serial No. 738,450. Term of patent 7 years.

To all whom it may concern:

Be it known that I, JOHN W. WADSWORTH, a subject of the King of Great Britain and Ireland, residing at Drayton, Staffordshire, England, have invented a certain new, original, and ornamental Design for a Plate or Similar Article, of which the following is a specification.

In the accompanying drawings, the figure is a plan showing the design.

I claim—

The ornamental design for a plate or similar article as shown.

In testimony whereof I affix my signature in presence of two witnesses.

JOHN WILLIAM WADSWORTH.

Witnesses:

WILLIAM DUDLEY,
JOHN H. COPESTAKE.
